PASTER

Filed June 28, 1928

Kris Hudson & Kent Attorneys.

UNITED STATES PATENT OFFICE

LESLEY R. TUFTS, OF EAST CLEVELAND, OHIO, ASSIGNOR TO THE CLEVELAND FOLDING MACHINE COMPANY, OF CLEVELAND, OHIO, A CORPORATION OF OHIO

PASTER

Application filed June 28, 1928. Serial No. 288,901.

This invention relates to improvements in pasters, that is apparatus for applying paste to sheets of paper moving through a paper handling machine, such for instance as a 5 folding machine. Devices of this character, as previously constructed, have been open to the objection that the width of the paste line which they applied was too great. This is practically unavoidable in the single disc 10 pasters heretofore used for the reason that paste clings to the sides of the disc as well as being collected upon the periphery thereof.

One of the objects of the present invention, therefore, is the provision of a paster 15 which shall be capable of applying paste in a fine line of constant cross section.

Another object is the provision of means within the paste well for agitating the paste and overcoming the difficulty, noticed in 20 previous constructions, of the disc or wheel which enters the well cutting a path through the paste and thereafter gathering an insufficient amount of paste.

A further object is the provision of means 25 for adjustably and removably mounting a paster of the character described.

Other objects and features of novelty will appear as I proceed with the description of 30 that embodiment of the invention which, for the purposes of the present application, I have illustrated in the accompanying drawings, in which—

Fig. 1 is a view of my paster in side elevation, fragments of a folding machine with 35 which it may be employed being shown in vertical section;

Fig. 2 is a plan view of the same, partly in section upon the line 2—2 of Fig. 1;

Fig. 3 is a vertical sectional view taken sub- 40 stantially on the line 3—3 of Fig. 2;

Fig. 4 is a front elevational view, partly in section upon the line 4—4 of Fig. 1; and

Fig. 5 is a detail sectional view on a magnified scale showing the relative positions of 45 the adjacent portions of the transfer and pasting discs.

In order to illustrate one possible applica- 50 tion of the invention I have shown in the drawings fragments of a folding machine of the buckle fold type including diagonal roll-

ers 10 of a horizontal feed table, a fixed plate 11 at the delivery end of said table, and a feed roll 12 which may be one of a set of rolls in a fold section. I have also illustrated at 13 a square bar extending across the machine 55 parallel to the shaft 12 which bar constitutes a support for the paster, and a rotating splined shaft 14 by means of which the paster mechanism is actuated. A sheet of paper traveling through the machine, and in the 60 process of being pasted, is indicated at A.

A bracket which carries the paster proper is shown at 15. It is clamped down upon the bar 13 by means of a clamping plate 16 and a stud 17 which is threaded into the bracket 65 from below. Additional clamping and adjusting studs 18 are threaded downwardly through the bracket to bear at their ends upon the bar 13, these latter studs being provided with locking nuts 19. By loosening the studs 70 17 the bracket 15 may be moved along the bar from one position of adjustment to another, after which the studs 17 may be again screwed inwardly to clamp the parts against movement.

Upon the shaft 14 I mount a pinion 19 which is keyed to turn with the shaft but is capable of longitudinal adjustment thereupon. The bracket 15 is provided with flanges extending inwardly toward the shaft 80 14 to engage the sides of pinion 19 and move is upon the shaft whenever the bracket is adjusted transversely of the machine. The bracket also carries a bushing or bushings 20 in which the shaft 14 rotates. It is not my 85 intention, however, to permit the shaft 14 to take a major portion of the load imposed by the weight of the paster, the bar 13 being the principal supporting element.

The paste container or well 21 is supplied 90 with a shouldered flange 22 which rests upon the upper end of bracket 15 and is removably secured thereto by means of a stud 23. The well has a hinged cover 24. At one end the bottom of the well is inclined inwardly as 95 indicated at 25, and the base of the well is also inclined downwardly and forwardly as indicated at 25', this being for the purpose of directing the paste toward the delivery portion of the well. This delivery portion is 100

provided with an open top compartment 26 into which paste is directed by mechanical means. The latter consists of an agitator disc or wheel 27 mounted upon a stub shaft 5 28 journaled in one end wall of the well. This disc extends through a slot in one wall of the compartment 26 and has a considerable surface exposed to the paste in the rest of the well.

10 29 is a gear casing that is provided with a pair of lugs 30, 31 secured to the well 21 by screws or the like. The shaft 28 extends into this casing where it carries a gear 32 that meshes with a gear 33 to be mentioned later.

15 On the forward wall of the well 21 there is a bearing lug 34 in which is mounted a shaft 35 that carries a paste transfer disc 36. The latter extends through a slot in the front wall of the well 21 into the compartment 26 20 at the bottom of the well. It also passes through a trough 57 on the outside of the well placed there to catch excess paste and direct the same back into the compartment 26. The shaft 35 also extends into the gear casing

25 29 where it carries the gear 33, above mentioned. Beyond the gear 33 shaft 35 carries another gear 37 which meshes with an idler gear 38 that rotates upon a shaft 39 mounted on the well 21. The gear 38 in turn meshes 30 with the pinion 19 on shaft 14 whenever the paster is in position upon the bracket 15.

Pivotedly mounted upon the shaft 35 there is a swinging arm 40, in the lower end of which is journaled a shaft 41 carrying a pasting disc 42 and also a gear 43 which meshes with gear 37. Above its paste point the arm 40 is provided with a finger 44, through which extends a threaded stem 45 that is anchored in the front wall of the well 21.

40 A knurled nut 46 is threaded upon the stem 45 and bears against the forward side of the finger 44, while a coil spring 47 bears against the rear side thereof. Threading of the nut 46 inwardly or outwardly, therefore, 45 serves to swing the arm 40 upon its pivot and to adjust the clearance between the pasting disc 42 and the paper A.

It will be observed that the periphery of the disc 36 is grooved in order to collect 50 paste readily, while the periphery of the disc 42 is V-shaped, that is with the point of the V outward, in order to deposit paste upon the paper in a fine line.

In the operation of the device, the well 21 55 being filled with paste, and the nut 46 being adjusted to bring the pasting disc 42 into the proper position above the paper A, power is transmitted from shaft 14 through pinion 19, and gears 38 and 37 to shaft 35, and thence 60 through gear 33 and gear 32 to shaft 28 upon which is mounted the agitator disc 27. The latter is thus rotated in the direction of the arrow in Fig. 3.

The disc 27 has a stirring action upon the 65 paste in the well proper, the paste being gen-

erally in a semi-fluid condition, and it also collects paste upon its side and edge surfaces and carries the same over into the compartment 26, the paste being stripped from the disc by the walls of the compartment on either side of the slot through which the disc passes. Furthermore, that part of the disc 27 which extends into the compartment 26 is in close proximity to the transfer disc 36, and hence is in a position to deliver paste directly 75 onto that disc and to keep the paste in compartment 26 in the neighborhood of disc 36 well mixed and relatively soft and fluid.

The rotation of the shaft 35 rotates transfer disc 36 in the direction of the arrow in 80 Fig. 3. This disc extends into the compartment 26 and collects paste therefrom in the groove in the periphery of the disc. This paste, or a portion of it, is delivered onto the V surface of the disc 42, the pointed edge of which cuts through the paste film B carried in the groove of the transfer disc 36, as illustrated in Fig. 5, and its even distribution over the surface is assured by the fact that gears 37 and 43 are made of different size so as to bring about a wiping action of one disc upon the other instead of a mere laying on of paste, as would occur if the discs rotated at the same speed.

The drive to the pasting disc 42 is such that 90 its lower periphery moves in the same direction as the paper A and preferably at a speed which is not greatly different from the speed of movement of the paper. However, it is desirable to maintain some difference in speed 100 between them in order to provide a wiping action here also.

The drawings and description herein have been made somewhat specific in order to fully disclose the invention in one of its forms, but 105 I desire to be understood that such disclosure is primarily illustrative in character and is not to be construed as limiting the invention.

Having thus described my invention, what 110 I claim is:

1. A paster for use in paper handling machines, comprising a paste well, said well having a compartment in the bottom thereof adapted to receive paste from said well, mechanically driven means for assisting the flow of paste into said compartment, and a rotating disc mounted outside of the well to extend into said compartment through a slot 115 in the well.

2. A paster for use in paper handling machines, comprising a paste well, a rotating paste transfer disc with a circumferentially grooved periphery arranged to gather paste from the paste well, and a rotating pasting disc having its periphery arranged to take 125 paste from the groove in said transfer disc.

3. A paster for use in paper handling machines, comprising a paste well, a rotating paste transfer disc with a circumferentially 130

grooved periphery mounted to extend into said well through a slot in the wall thereof, and a rotating pasting disc arranged to contact with paste in said grooved periphery,
5 said pasting disc being adapted to cause the paste upon its periphery to contact with the surface of paper moving through the machine.

4. A paster for use in paper handling machines comprising a paste well, a grooved rotating paste transfer disc arranged to gather paste from the paste well, and a rotating pasting disc having a V-shaped periphery arranged to contact with paste carried in the
15 groove of said transfer disc.

5. A paster for use in paper handling machines, comprising a paste well, said well having a compartment in the bottom thereof adapted to receive paste from said well, mechanical means for assisting the flow of paste into said compartment, a rotating transfer disc and a rotating pasting disc, said transfer disc being mounted outside of the well to extend into said compartment through a slot
25 in the well, and being arranged to transfer paste from said compartment to the periphery of said pasting disc.

6. A paster for use in paper handling machines, comprising a paste supply, a rotating transfer disc, means enabling said disc as it rotates to gather paste from said supply, a supporting arm mounted to swing upon an axis concentric with the axis of said transfer disc, a pasting disc rotatably mounted upon
35 said arm with its periphery adjacent the periphery of said transfer disc, and adapted to be arranged directly above a horizontal sheet to be pasted, means for rotating said transfer and pasting discs, and means for
40 regulating the angular position of said arm, whereby the position of said pasting disc with respect to the paper to be pasted may be controlled.

In testimony whereof, I hereunto affix my
45 signature.

LESLEY R. TUFTS.
